OF D 13,272

THE IVY.

UNITED STATES PATENT OFFICE.

WERTER C. HIGGINS, OF NORWICH, CONNECTICUT.

DESIGN FOR A STOVE.

SPECIFICATION forming part of Design No. 13,272, dated August 29, 1882.

Application filed July 12, 1882. Term of patent 14 years.

To all whom it may concern:

Be it known that I, WERTER C. HIGGINS, of Norwich, in the county of New London and State of Connecticut, have invented a certain 5 new and useful Design for a Stove, of which the following is a full, clear, and exact description, reference being had to the accompanying engraving, forming part of this specification.

This invention embraces the following features: first, a design for the top plate of a parlor or other heating-stove; second, a design for the panels on the stove; third, a design for the doors of the stove; fourth, a design for ornamenting the base and legs of the stove; fifth, a 15 design for the front and sides of the main or central portion of the stove; sixth, a design for the top of the stove; seventh, a design for the crest forming the extreme top of the stove.

Referring to the letters of reference marked 20 on the accompanying engraving in further describing the features of the design, the top plate, A, is a rectangular plate provided with a broad overhanging edge, *a*, from which it rises in two steps, and two slightly-concaved 25 surfaces toward the center, where it forms a level rectangular top, the second step and the inclined concaved surface forming the hinged portion of the top plate, and being provided with the knob or handle *a'*, the step *a*² marking the 30 dividing-line between the fixed and the hinged parts of the top plate, A. Both of the concaved surfaces forming the top plate are ornamented—the lower with an edging pattern and the upper with ivy vines and leaves. The overhanging edge of the plate may be burnished.

The panels B and B' resemble each other, in 35 that on both an ivy-vine is produced in cameo or raised work. The panels B are placed on each side of the stove on the base portion of 40 the same, while the panels B' B' form borders around the doors, both on the front and sides of the stove, and in these the ivy-vine twines through the length of the panels. The proportions of these panels and the configuration 45 of the ivy-vines are clearly shown in the engraving.

The design for the doors C of the stove consists in the frame, the bars of which are curved outward, so as to give the whole door a convex 50 form. The frame is ornamented with ivy-vines, as is clearly shown in the engraving. They

are arranged to receive lights of mica, which, when the fire is burning, give to the convex doors C a peculiar and striking appearance.

The design for the base D consists of the 55 plate, projecting on each side sufficiently to form a molding, but projecting considerably more in the front of the stove. The plate is surrounded by the wide nearly vertical edge *d*, which may be burnished, if desired. Beneath 60 this edge the scalloped border E connects with the legs *ee*, on which vases are produced, from which ivy-vines spring, spreading and twining over the border E, as is clearly shown in the 65 engraving.

The design for the front and sides of the central portion of the stove consists of a case rectangular in cross-section, the corners being formed by the rounded beads *ff*, the sides of which pass beyond the surface to a re-entering angle extending to the surface of the plates, thus forming a groove on each side of the rounded corner.

The convex doors C C are surrounded by the ornamental panels B' B'; the upper horizontal 75 panel, B', having the raised segmental pediment *g*, all of which is clearly shown in the engraving hereunto annexed.

The design for the top portion of the stove consists of a rectangular portion of less width 80 and breadth than the main portion of the stove, divided from the main portion by the overhanging plate K, the edge of which may be burnished, the top surface of which plate K is molded and extends inward until it meets the 85 rectangular top, as is clearly shown in the engraving.

I I are plates ornamented with ivy-vines. These plates may be of iron, porcelain, tile, or any other suitable material or color without 90 altering the general spirit of the design, as shown in the engraving.

On the ash-pit box L' the plate L, made with an overhanging edge, is placed, projecting equally on the front and sides over the ash-pit 95 box, and provided with a rounded projection, *l*, on the side where the grate is operated. The central and main portion of the stove rises from the plate L, being of the same breadth as the ash-box, but of sufficiently less depth to leave 100 a wide portion of the plate L exposed in front. Above this main portion the stove is contracted

inward to the part formed by the panels I I, which portion is surmounted by the top plate, on which the final ornament rests.

The design for the final or extreme top of the 5 stove consists of the rectangular plate II, the sides of which are cut out on curved lines, as is shown in the engraving, so that the four corners only rest on the top plate of the stove. The figure of a sphinx is represented as resting on the plate II; but any recumbent or couchant natural or mythological animal might be substituted for the sphinx without departing from the spirit of my design.

Having thus described my invention, I claim 15 as new and desire to secure by Letters Patent--

1. The design for the top plate of a stove, the same consisting of the overhanging edge *a* and the ornamented concaved surfaces *a' a'*, separated by the step *a²*, substantially as shown 20 and described.

2. The design for the stove-panels B B', ornamented with ivy-vines, substantially as shown and described.

3. The design for stove-doors, the same consisting in a frame divided by bars into panels, said bars being ornamented with ivy-vines, the whole forming a convex door, as shown 25 and described.

4. The design for the base of the stove, the 30 same consisting in a scalloped border, the

scalloped edge of which connects with the outline of the legs, the legs ornamented with a vase, from which ivy-vines spread over the leg and border, as shown and described.

5. The design for the central portion of a 35 stove, consisting in a body rectangular in cross-sections, having the beads *f f* at the corners, the front and sides provided with convex doors surrounded by the panels B', as shown and described.

6. The design for the top of the stove, consisting of a rectangular portion of the stove set in from all sides and divided into panels ornamented with designs, as shown and described.

7. A design for the crest-plate of a stove, consisting in the rectangular plate supported on four corner-feet formed by the end portions of the sides, the lower edges of these sides being cut away between the feet, substantially as 50 shown.

8. A design for the crest of a stove, consisting in a rectangular plate supported on four corner-feet and surmounted by a recumbent or couchant animal, substantially as shown.

WERTER C. HIGGINS.
